CLOSURE ELEMENT FOR AIR DUCTS

Donald H. Stroup, Cleveland, Ohio

Application January 3, 1949, Serial No. 68,987

4 Claims. (Cl. 98—119)

1

My invention relates to an improved closure element for air ducts used with ventilating fans of the type commonly employed in domestic use. It has been the practice to install fans of this type in an upper wall of the kitchens, of modern homes, said fans being operated by push buttons or the like, a conduit leading air drawn by the fan through an air duct, or a conduit to an opening cut in the siding on the exterior of the house. Different types of closure elements have been placed in the siding to close the end of such conduits and these have generally involved the use of a plurality of louver boards, shutters, or the like. These louvers swing to open position when air is being forced through the conduit and when the fan is operating. When the fan is disconnected these are hingedly inter-connected in such a manner that they fall back in lapped conduit closed position. One of the defects inherent in such constructions resides in the fact that these are not securely held in closed position and hence are susceptible to being acted upon by air on the outside of the house and whenever a fairly strong breeze is blowing, the louvers have a tendency to be lifted from the outside by the wind and to open and shut according to the velocity of such wind resulting in an objectionable "flapping" noise which may further result in damage to the shutters or louvers themselves.

It is an object of my invention to provide a closure element for conduits of the type aforementioned which may easily be opened by greater than atmospheric pressure to permit passage of air from the interior of the house when the fan is in the "on" position and which will also be securely held in conduit closed position when the fan is in its "off" position.

Another object of my invention is to provide an improved closure element of the type referred to composed of but few operating parts, economical in manufacture and highly efficient in use.

Other objects of my invention and the invention itself will become more readily apparent from a perusal of the description which follows, in which description reference will be made to the appended drawings.

In the drawings:

Fig. 1 is a side plan view of the device of my invention, the closure element and associated means being shown in solid line in the fan "off" position and in dotted lines in the fan "on" position;

Fig. 2 is a front plan view of the device of Fig. 1 in the solid line position of Fig. 1;

Fig. 3 is a front plan view of the device of Fig. 1 shown in the fan "on" position;

2

Fig. 4 is a side plan view of the device of my invention in an intermediate position between the final fan "on" and fan "off" position;

Fig. 5 is a side plan view of a part of the device of Figs. 1 to 4 inclusive, said portions being broken away to show the stem clearly.

Fig. 6 is a side plan view of an embodiment of my invention, the closure element and associated means being shown in solid line in the fan "off" position and in dotted lines in the fan "on" position;

Fig. 7 is a front plan view of the device of the embodiment of my invention of Fig. 6, shown in solid line position;

Fig. 8 is a front plan view of the device of the embodiment of my invention of Fig. 6 shown in the fan "on" position;

Fig. 9 is a side plan view of the device of the embodiment of my invention in an intermediate position between the final fan "on" and fan "off" position;

Fig. 10 is a side plan view of a part of the embodiment of Figs. 6 to 9 inclusive, said portions being broken away to show the stem clearly.

Referring now more particularly to the drawings in all of which like parts are designated by like character references, at 10 I show an elongated box like air duct or conduit. As will be well understood in the art, this conduit extends through an opening in the walls of the house from the exterior siding to the interior wall and a fan is adapted to be associated therewith on the interior wall of the house and air adapted to be drawn by the fan into said passage.

The closure element 11 is shown as a single flat louver board or shutter but may be composed of a plurality of overlapping louver boards; it is adapted to completely cover the conduit openings and, as best shown in Fig. 2, is hingedly connected to the conduit 10 by means of a pair of flat louver supporting members 12 bolted or otherwise fastened to the upper face of the side portions of the conduit 10 by bolts 13, screws or the like, a portion of each said member 12 being adapted to project forwardly of the outer face of the conduit 10 and to carry hinging means 14 adapted to be secured to the upper portion of the louver or flap element 11.

Centrally of the forward face of the louver board 11 a U-shaped clip 14 is secured and aligned therewith. At the upper portion of the forward face of said element 11 is a relatively large U-shaped clip 16 which projects outwardly a substantially greater distance than the U-shaped clip 15 from the forward face of the louver board 11. A weighted element 20, with

an elongated stem 21 having a U-shaped slot 22 at one end thereof and carrying an enlarged cylindrical weight 23 at its opposite end, is adapted to be carried by the louver board 11. The stem 21 of the element 20 is telescoped through the U-shaped clip 16 and disposed over the yoke of the U-shaped clip 15 wherefor the stem is fulcrumed upon the U-shaped clip 15. The stem 21 is of such dimensions that it is adapted to move towards the outer face of the louver and away from the same a distance limited by the distance which the U-shaped clip 16 projects forwardly from the outer face of the louver board. It has been found desirable that the weight 23 be slightly less than the weight of the element 11 and that the weight 23 plus the weight of the element 11 be greater than normal atmospheric pressure.

It will be noted that the weight 23 is disposed forwardly of the hinged connection of the element 11 and the conduit 10 when the fan is in its normal "off" position and the louver or shutter then is maintained in complete closure of the conduit. Upon the force of an air flow greater than atmospheric pressure, when the fan is in its "on" position, the weight 23 acts as a weight slightly beyond the initial opening position of the louver and the air force in the conduit or air duct must be sufficient to overcome the force of said weight and the weight of the element 11 in order to force the element 11 away from the outer face of the conduit. As said door opens, the flap 11 is lifted upwardly under the pressure of greater than atmospheric pressure wherefor the weight 23 falls back within the U-shaped clip 16 and against its yoke, and such weight then passes the hinge point 14 at which point the weight draws the flap 11 up to the position shown in Figs. 1 and 3 and the weight 23 now acts as a counterweight counter-balancing the weight of the flap 11 to hold said flap up. A slot or channel 25 in the wall of the house above the conduit opening is provided within which the weight and its associated stem 21 may travel in an arcuate path from the position shown in solid lines in Fig. 1 to the position shown in dotted lines therein.

When the fan is turned "off," the weight of the flap 11 being greater than the weight of the weight 23 will more than balance the counter-weight 23 and the flap and element 20 will return to the position shown in Fig. 4 at which point the element 20 will drop back against the yoke of the U-shaped clip 16 to act as a secure closing and locking means to maintain the flap 11 in secure closed engagement with the conduit and the weighted element 20 will offset any external force such as a heavy wind etc. and will maintain the louver 11 in such closed engagement until it is subject to greater than atmospheric pressure exerted against the flap 11.

In the form of my invention shown in Figs. 6 to 10 inclusive at 60 I show an elongated box-like air duct or conduit similar to the conduit 10 in the form of my invention shown in Figs. 1 to 5 inclusive. The closure element 61 in this form of my invention is a flat louver board or shutter adapted to cover a substantial portion of the forward face of the box-like enclosure 60 and a portion of the slanted board 50 which is secured to the inner surface of the upper face 40 of the conduit 60 at a forward portion thereof such as indicated at x, said board being further secured to the opposite sides 30-30 of the conduit 60 as shown at y, a triangular shaped

chamber being thus formed in the upper forward portion of the conduit. The element 61 is secured to the conduit 60 by means of a pair of flat louver or shutter supporting members 62, bolted or otherwise secured to the outer face of the side portions 30 of the conduit 60 by bolts 63, screws, or the like, a portion of each member 62 being adapted to project forwardly of the sides 30 of the conduit and to carry hinging means 64 adapted to be secured to the upper portion of the louver, or flap element 61. The hinging means 64, in this embodiment of my invention, preferably comprises a cylindrical rod 65 telescoped through the upper portion of the flap 61 and journalled in the forwardly extending portions of the member 62. The uppermost edge of the element 61 is preferably provided with a pair of narrow U-shaped slots 66, said rods 65 projecting therethrough. A weighted element 70, comprising an elongated cylindrical weight 71 having a downturned leg 72 disposed at either end thereof, is adapted to be rotatably journalled upon said rod, an aperture 73 slightly larger than the outer diameter of the rod 65 being provided in each leg 72, said rod passing through each said aperture of the legs which extend downwardly into the slots 66. Intermediately of the element 61 and at the upper portion of said element on opposite faces of the element 61, a pair of generally inversely L-shaped elements 75, 75a are secured, as by screws 76 or the like. Each of the L-shaped elements are disposed with their footed upwardly extending portions 76, 76a flaring outwardly in opposite directions on either side of the weighted element 70 and the weight 71 is adapted to rest upon either the portion 76 of the element 75 disposed on the outer surface of the element 61 as best shown in solid lines in Fig. 6 when the fan is in its fan "off" position, or against the portion 76a of the L-shaped element 75a disposed on the innermost face of the element 61 when the fan is in its fan "on" position as best shown in dotted lines in Fig. 6 or as shown in Fig. 10, in which final "on" position, as shown in Fig. 10, the weight also rests against the slanted board 50. The weight 71, in this embodiment of my invention, operates similarly to the weight 23 in the first embodiment of my invention. In other words, under the force of an outgoing air flow within the conduit greater than atmospheric pressure, when the fan is in its "on" position, the weight 71 acts as a weight tending to restrain opening of the flap 61 until the force of the air within the conduit is sufficient to overcome the combined weight of the weight 71 and the flap 61 whereupon the flap or door 61 is forced open and the element 61 is lifted up under the effect of pressure greater than atmospheric pressure. The weight 71 then falls back against the portion 76a of the element 75a disposed on the inner face of the flap, which is back of the hinged connection of the flap and its bracket supports 62. At this point the weight 71 begins to act as a counter-weight counterbalancing the weight of the flap and assists in holding the flap or door open as shown in Fig. 10. Conversely when the fan is turned "off," the weight of the flap being slightly greater than the weight 71 will return the flap to its initial conduit closed position and the weight will swing back to the position shown in solid lines in Figs. 1 and 7 and the weight will maintain the flap in secure closed engagement with the forward face of the conduit.

The channel or compartment formed by the slanted board 50 and the inner face of the upper portion of the conduit and of the side portions of the conduit will, it is believed, assist in holding the flap or shutter closure element 61 in secure engagement against the face of the conduit by drawing a portion of any outside air forces or wind into the triangular compartment where it will exert a force against the weight to hold the weight even more securely in engagement with the portion 76 of the element 75 mounted on the outer face of the flap 61.

Although I have described my invention in connection with said preferred embodiments thereof, it is to be understood that numerous changes and various departures may be made therefrom as, for example, using multi-louvers or side placement of the weighted elements, without, however, departing from the spirit of my invention and the scope of the appended claims.

I claim:

1. In an air outlet device, a source of air flow greater than atmospheric pressure, said air flow adapted to be turned "on" and "off," the said air flow flowing through said conduit, a flap element hingedly secured to said conduit, a weighted element consisting of a stem and a weight, pivot means secured to a center portion of said flap element and extending outwardly therefrom, guide means secured to said flap element above said pivot means and extending outwardly of the flap element, said stem being telescoped through said guide means and pivoted upon said pivot means, the weight being disposed upwardly of the flap element wherefor the weighted portion of said weighted element is disposed outwardly of said hinged connection of the conduit and the flap element when the air flow is "off," said weighted element, when the air flow is "on," being adapted to operate as a counterweight holding said flap element away from the conduit opening when said weight passes the hinged point under the force of air flow of greater than atmospheric pressure exerted upon the flap.

2. In an air outlet control device, an air outlet conduit, a closure element for said air outlet conduit hingedly secured to the upper portion of said conduit, a weighted element comprising a support member adapted to be pivotally mounted upon said closure element and a weighted member adapted to be supported by said support member above the hinged connection of said closure element and said conduit, guide means secured to said closure element disposed adjacent said hinged connection of said closure element and said conduit and being so disposed with respect to said weighted member as to control the extent of pivotal movement of said weighted element, said weighted member operating as a weight when pivoted forwardly of the hinged connection of the closure element and air outlet conduit assists in closing and holding the closure element against the air outlet conduit and operating as a counterweight when positioned rearwardly of the said hinged connection to assist in opening and holding the closure element away from the air outlet conduit.

3. In an air outlet control device, an air outlet conduit, a closure element for said air outlet

conduit hingedly secured to the upper portion of said conduit, a weighted element comprising a support member adapted to be pivotally mounted upon said closure element and said conduit, said weighted member adapted to be supported by said support member above the hinged connection of said closure element and said conduit, said weighted element being of a weight slightly less than the weight of the closure element, guide means secured to said closure element disposed adjacent said hinged connection of said closure element and said conduit and being so disposed with respect to said weighted member as to control the extent of pivotal movement of said weighted element, said weighted member acting as a weight when pivoted forwardly of the hinged connection of the closure element and air outlet conduit to assist in closing and holding the closure element against the air outlet conduit and operating as a counterweight when positioned rearwardly of the said hinged connection to assist in opening and holding the closure element away from the air outlet conduit.

4. In an air outlet control device, an air outlet conduit, a closure element for said air outlet conduit, hingedly secured to said conduit, said closure element being so disposed and of such size as to cover the air conduit opening, means secured to and projecting outwardly of said closure element, a weighted element comprising a support member and a weighted member, said weighted element being pivotally mounted upon said first named means, said weighted portion of said element being disposed above said closure means, guide means secured to and projecting outwardly of said closure element, said guide means disposed upwardly of and substantially in alignment with the said first named means, said guide means being so disposed with respect to said weighted element as to control the extent of movement of said weighted element with respect to said closure element, said weighted element operating as a weight when positioned forwardly of the hinged connection of the closure element and air outlet conduit to assist in closing and holding the closure element against the air outlet conduit and operating as a counterweight when positioned rearwardly of the said hinged connection to assist in opening and holding the closure element away from the air outlet conduit upon the application of air internally against the closure element.
